UNITED STATES PATENT OFFICE.

SAMUEL W. RUSHMORE, OF PLAINFIELD, NEW JERSEY.

COOLING SYSTEM.

Application filed December 7, 1920. Serial No. 428,885.

To all whom it may concern:

Be it known that I, SAMUEL W. RUSHMORE, a citizen of the United States, and resident of Plainfield, in the county of Union 5 and State of New Jersey, have invented certain new and useful Improvements in Cooling Systems, of which the following is a specification.

My present invention relates to cooling 10 systems adapted for use with internal combustion engines and particularly to those adapted to operate by the boiling and condensing cycle, with the radiator functioning as an upflow condenser. The generic features of construction, the operation, and the 15 advantages of such functioning are set forth in my Patent No. 1,378,724, granted May 17, 1921.

In its preferred embodiment the invention 20 includes a force-feed circulation serially through a heat absorption circuit of radiating capacity barely sufficient, or even insufficient, to continuously cool the motor by water cooling methods, in combination with 25 a supplemental induced or thermal circulation through a radiating circuit, arranged, so to speak, in shunt on the force-feed circulation and adapted to automatically come into play proportionally as the heat evolution 30 in the engine increases and thereby raises the temperature of the discharged water. This induced or thermal circulation attains maximum activity when the temperature is high enough to cause free evolution 35 of steam. These circuits may be provided by connecting an ordinary force pump circuit through the space in the bottom of the radiator, preferably with the inlet and outlet so located and relatively arranged that 40 a very low resistance path is afforded from the jacket water inlet, across to the outlet which leads to the pump in the water jacket. Thus arranged the radiator proper is not in series with the water circulation, but is in 45 position to afford a shunt path to which hot water and steam may escape. With this arrangement, starting the engine will cause the pump to circulate a small amount of water in substantially closed circuit through 50 pump, water-jacket, piping and the intermediate low resistance path between inlet and outlet at the bottom of the radiator. This small body of water used over and over again will be heated preferably to boiling 55 point.

As it is desired that the low resistance

cooling path of the water across the bottom of the radiator be of relatively small capacity it is evident that when only this part of the radiator is filled, the surplus available 60 for pump leakage and other ordinary losses will become rather small, hence I prefer to arrange an auxiliary tank in which the surplus water may be stored, and this tank is preferably arranged as an over-flow from 65 the radiator, which may be filled primarily by hand or which may become filled by trapping a predetermined supply of water, when water in the honeycomb is forced out by steam in the manner described above. 70

The above and other features of my invention may be more fully understood from the following description and the accompanying drawings in which:—

Figure 1 is a side elevation conventionally 75 indicating an internal combustion engine, an air cooled radiator as commonly employed on automobiles, etc., but having one form of my invention applied thereto;

Figure 2 is a vertical section of the radiator.

Fig. 1 shows the usual crank case 1 and cylinder block 2 of a four cylinder motor of the automobile type, the upper parts of which are enclosed by water jacket 3. The 80 water cooling system is conventionally indicated as including the radiator 4 preferably located on the same level with the motor and directly in front of it. The circulation of the water from the bottom of the radiator, is 85 through a conduit comprising outlet 5, flexible coupling 6, check valve 7 and pipe 8 to pump 9, which may be of any known or desired construction, but which is here indicated as being an ordinary centrifugal 90 pump. The pump discharges through a conduit including pipe 10, branches 15, 16, water jackets 3, outlet pipe 17, 18 and a single return pipe 19. The above parts may 95 be of any known or desired construction. 100

The return pipe 19 is connected to the bottom of the radiator, as by flexible joint 23 and downward pipe 24 which, if desired, may be recurved as at 25 so as to enter the radiator through the bottom. 105

The radiator is specially designed so that the amount of water circulating at the bottom of the radiator may be relatively small, and so that the honeycomb may act almost entirely as a steam condenser, yet with provision for a reasonable reserve supply of water to compensate for leakage and other 110

losses. As shown in Fig. 2 the honeycomb cooling area is considerably reduced, this being made possible by the above referred to increase of efficiency due to working at higher initial temperatures. The space so saved at the top of the radiator is utilized as a reservoir 30 communicating with the honeycomb compartment through standpipe 31. This reservoir 30 communicates with the intake of the pump through pipe 32 which may be provided with a cock 33 through which water may be drawn off. Flow of water from this source downward from the pump, through conduits 8, 6, 5 into the bottom of the radiator, is preferably prevented by means of the check valve at 7. When the ordinary centrifugal pump is employed, this check valve also operates to prevent blowing back of water from the jacket into the bottom of the radiator, if the engine is stopped while hot enough to generate considerable quantities of steam.

As shown in these Figs. 1 and 2, the discharge inlet is in the form of an elbow casting 26^a directly confronting a similar casting 5^a, which is the intake for pipe 5 which leads to the pump. This affords a specially low resistance path for circulation of water at the highest temperature yet affording opportunity for upward escape of steam.

This apparatus is especially designed so that in normal operation the level of the water in the bottom of the radiator may be kept at the bottom of the honeycomb as indicated, the reserve supply being in a reservoir 30.

This apparatus may be started by removing cap 21 and filling the reservoir 30 with water and permitting it to overflow through pipe 31 until the circulating system and water jackets have been filled by running the

engine at sufficient speed, and until a further definite amount has collected in the bottom of the radiator. Thereafter water drawn from reservoir through pipe 32 and thus getting into circulation, may accumulate in the bottom of the radiator to a certain extent, but whenever the accumulation becomes too great the steam coming in through 26^a and rising through the vertical passages will tend to project the excess water up through pipe 32. 45 50

I claim—

1. In a cooling system for internal combustion engines, a force feed water circulating system of small heat radiating capacity serially including a water jacket, a water outlet conduit from said jacket, a water container to which said outlet is connected, and a return conduit including a pump between said container and jacket, in combination with an air cooled element of large radiating capacity above said water container, interposed between it and an outlet for escape of air, steam and hot water; and a reservoir 65 interposed between the air cooled element and the air outlet, arranged to trap water driven through the air cooled element in the operation of the device, and means for returning the trapped water to the cooling 70 water circuit.

2. In the combination specified by claim 1, the further feature of having the reservoir located above the top of the air cooled element, and a small capacity conduit leading 75 from the reservoir to the intake of the pump, as the means for returning trapped water to the cooling circuit.

Signed at New York, in the county of New York, and State of New York this 6th 80 day of December, A. D. 1920.

SAMUEL W. RUSHMORE.
